ATTORNEY

UNITED STATES PATENT OFFICE.

EARL STROMINGER, OF STOCKTON, CALIFORNIA.

FIRE-PLUG.

1,287,508.

Specification of Letters Patent. Patented Dec. 10, 1918.

Application filed March 30, 1917. Serial No. 158,688.

To all whom it may concern:

Be it known that I, EARL STROMINGER, a citizen of the United States, residing at Stockton, in the county of San Joaquin 5 and State of California, have invented certain new and useful Improvements in Fire-Plugs, of which the following is a specification.

My invention has reference to hydrants or 10 city fire plugs and has for its purpose the provision of a fire plug which may be disposed beneath the surface of the city pavement in such a manner as to be concealed from view, while at the same time, being 15 readily accessible in case of emergency. By such arrangement, I propose to assist in the beautifying of a locality by removing from its thoroughfares all unsightly obstructions or obstacles such as the projecting type of 20 fire plug hydrant so common to the larger cities and which are supported externally of the pavements thereof.

A further object is to provide a hydrant 25 of the character described which has provided thereon a plurality of separate and independent hose-connections, each having a separate valve mechanism and capable of being used without interfering with the use of the other connections.

30 A still further object of the invention is to provide a fire plug which has a number of out-let cylinders, capable of being separately connected to a plurality of hose lengths, thus providing a source of water 35 supply for several fire engines at the same time.

With these objects in view, the invention consists in the novel construction and arrangement of parts, as will be hereinafter 40 described and claimed, reference being had to the accompanying drawings in which:

Figure 1 is a sectional view taken through the sunken inclosure and illustrating the position of the fire plug therein, and

45 Fig. 2 is a top plan view, illustrating the curvature of the water chest, the position of the out-let cylinders or plugs, and also the rectangular casing which may be employed for housing the parts of the device below 50 the level of the ground, as represented in Fig. 1.

Referring more specifically to the drawings, 1 and 2 represent sections of an underground water supply pipe or main through 55 which a city receives its water supply. At

a suitable place the soil is removed from about the main so as to provide a recess 3, which has its open end 2 substantially level with the sidewalk or road 4, as the case may be. In depth, this recess should extend beneath the sections 1 and 2 a sufficient distance to permit the water chest 5 to be connected to and to unite the sections 1 and 2 of the water main. As will be noted, this water chest has the flanged portions 6 into 60 which the opposed end of the sections 1 and 2 are adapted to be securely received and provides a continuous passage way or conduit for the water.

The center portion 7 of the main is positioned out of the direct path of the water as it is discharged into the end of the water chest, as will be clearly understood from Fig. 2, in which the arcuate or curved formation of the water chest is clearly shown. 70 The water as it enters the chest from either of the sections 1 and 2 will then be caused to swerve in its direction as it passes through the chest, being momentarily halted before its passage into the opposite section of the 75 main. As the discharge or out-let cylinders are positioned directly above the arcuate base portion of the water chest, the suction exerted therethrough, by means of the first 80 engine or other pump attached thereto, will 85 take immediate advantage of the momentary check in the flow of water through the water chest so that it will be drawn in full quantities through such of the out-let cylinders as may be in use, without effecting, to any 90 material extent, the ordinary flow of water in its usual passage through the water main.

The upper portion of the water chest extends upwardly in a restricted curve to provide a neck portion 8 into which the water 95 is adapted to accumulate and to be fed through the cylinders or plugs 9. Each of the plugs 9 extend substantially in a vertical direction from the neck portion 8 of the water chest and have their lower ends 10 issuing into chamber and compartment 11 100 which is common to all of them. The upper flanged ends 12 of the plugs are positioned to terminate beneath the open end 2 of the recess 3 but lying in proximity thereto so 105 that connections may be readily made to each plug. Suitable valve mechanism 13 is provided upon each of the plugs and may be operated to open or close the plug independently of the other cylinders.

In order that the hydrant may be housed and protected in an appropriate manner, a receptacle 14 of metal, wood, or any suitable material adapted to protect and preserve the working parts of my invention in good working condition, may be employed. This receptacle 14 is inserted in the sunken recess 3 and is of course, provided with the necessary openings to permit the ends 1 and 2 of the water main to pass therethrough in a manner previously described. Over the open end of the recess of sunken receptacle 14 is arranged a suitable cover 15 which is adapted to lie flush with the surface of the ground or pavement and which conceals the fire plug from view.

In use, the hydrant is very easily and quickly brought in operation, it merely being necessary to remove the cover means 15 which is to be so positioned as to be capable of being removed in an instant so as to permit of ready access to the plug 9. After making the proper connection to as many of the plugs as may be thought advisable, the valve wheel 16 of each plug may be promptly adjusted so as to open the valve and permit the water to be drawn from the mutual supply chamber 11 into those plugs being used. If desired, suitable packing may be arranged within the receptacle to surround and keep the lower parts of the device in constant working condition and to protect it to some extent against inoperativeness caused by freezing, etc.

Although the above description refers to what might be considered the preferred embodiment of the invention, it is to be clearly understood that certain changes in the details of construction, arrangement and proportionment of parts may be resorted to within the scope of the appended claims.

without sacrificing any of the advantages thereof.

What I claim as new and desire to secure by Letters Patent is:—

1. In a hydrant, the combination with a receptacle disposed within a recess and having openings formed in certain of the opposite walls thereof, of main-pipe sections projecting through said openings, a water chest in said receptacle disposed to lie in the path of said main-pipe and connected thereto, said water chest being of arcuate formation so as to halt the passage of water temporarily, a plurality of vertically disposed out-let cylinders arranged on said water chest, said cylinders having their lower extremities united to provide a reservoir common to all of the cylinders and having their upper out-let ends subjacent to the opened end of the recess, and removable means for covering said recess and receptacle.

2. In a hydrant, the combination with a receptacle disposed within a recess and having openings formed in certain of the opposite walls thereof, main pipe sections projecting through said openings, a water chest in said receptacle disposed to be in the path of said main pipe sections and connected thereto, said water chest being of arcuate formation so as to halt the passage of water before it enters the other section of the main pipe, and a plurality of valve regulated cylinders or plugs extending in a vertical position from the water chest.

In testimony whereof I affix my signature in presence of two witnesses.

EARL STROMINGER.
